UNITED STATES PATENT OFFICE.

JOSEPH E. FAWELL, OF PITTSBURGH, PENNSYLVANIA, ASSIGNOR TO MACKINTOSH-HEMPHILL COMPANY, OF PITTSBURGH, PENNSYLVANIA, A CORPORATION OF PENNSYLVANIA.

ROLLING MILL

Application filed September 29, 1921. Serial No. 504,119

To all whom it may concern:

Be it known that I, JOSEPH E. FAWEELL, residing at Pittsburgh, in the county of Allegheny and State of Pennsylvania, a citizen of the United States, have invented or discovered certain new and useful Improvements in Rolling Mills, of which improvements the following is specification.

The invention described herein relates to certain improvements in manipulating mechanism for rolling mills of the type or construction shown and described in Letters Patent No. 1,131,604, granted to me March 4th, 1915, and has for its object a construction of mechanism whereby the pieces being reduced may be axially rotated on one side of the reducing rolls and axially rotated and shifted laterally on the opposite side of the reducing rolls. The invention is hereinafter more fully described and claimed.

In the accompanying drawing forming a part of this specification, Fig. 1 is a plan view of a mill embodying the improvements claimed herein; Figs. 2 and 3 are sectional elevations of the mill, the planes of section being indicated respectively by the lines II—II and III—III Fig. 1; Fig. 4 is a sectional elevation of the driving pinions and housings; Figs. 5 and 6 are diagrammatic views showing the shapes of passes in the respective pairs of rolls; Fig. 7 is a plan view of a portion of the feed table on the receiving side of the mill; Figs. 8, 9, and 10 are sectional elevations showing the different positions of the manipulating devices in laterally shifting and turning the pieces on the receiving table; Fig. 11 is a plan view of a portion of the delivery tables; and Figs. 12, 13 and 14 are sectional elevations showing the operation of the devices for turning the pieces on the delivery table.

The mill is constructed substantially as shown and described in Letters Patent No. 1,136,604, above referred to and consists of two pairs of reducing rolls 1 and 2, having their journals arranged in windows 3 in discs 4, said windows being so arranged that in one position of the discs one pair of rolls as 1 will have their axes in a common vertical plane, while the other pair of rolls will be in such a position that a horizontal plane passing between the rolls 1' will be tangent to the journals of the rolls 1.

tial or approximately so to the highest part of the upper roll of the pair 2 so that said roll will serve to support and feed an article being reduced in the rolls 1' and moving to the left in Fig. 2. When the discs are shifted the positions of the two pairs of rolls will be reversed, the rolls 2 being moved to operative or vertical position and the rolls 1' moved to a position that will permit of the upper roll to support and aid in moving an article passing to the right through the rolls 2. The discs 4 are preferably supported on rollers 5 mounted in pillow blocks 6; shafts 7 and 8 which are adapted to be oscillated as hereininafter described, are mounted in suitable bearings on opposite sides of the discs and on these shafts are secured arms 9 and 10 connected by links 11 to a pin 12 passing through lugs 13 on a spacing frame 14 secured between the discs as shown in Figs. 2 and 3. An arm on one of the shafts, as 8, is connected by a pitman 15 to an arm 16 on a shaft 17, which is adapted to be oscillated by fluid pressure cylinders 18.

The journals at one end of the respective rolls are connected by couplings 19 to spindles 20 which are also connected by similar couplings 21 to journals of pairs of pinions 22-23. As shown, each pair of rolls is connected to a pair of intermeshing pinions and one pinion of one pair as 22 intermeshes with a pinion of a third pair 85 of pinions 24, and the other pinion of this latter pair intermeshes with a pinion of the pair of pinions 23, as will be seen by reference to Figs. 1, 3 and 4. The driving shaft 90 may be connected to a journal of any one of the pinions as for example with one of the pinions of the pair 24 which is shown with a projecting journal 25 for connection with such driving shaft.

As shown in Figs. 1 and 2, feed tables A 95 and B are arranged on opposite sides of the mill and provided with driven and reversible rollers 26 which are grooved in line with the passes in the reducing rolls. In the construction and arrangement shown herein the 100 article to be rolled is transferred from the furnace to the table A, and the finished article is removed from the table B, and hence for convenience the table A will be termed

the receiving table and the table B as the delivering table. By reference to Figs. 1 and 2 it will be seen that articles placed on the receiving table A pass between rolls 1 and over rolls 2 onto the delivering table and on the back pass or when the mill and feed rollers are reversed, the articles pass through rolls 2 and over rolls 1 onto the receiving table B.

10 The improvement claimed herein is especially adapted to a method of reduction known in the art as the "square and diamond" method of reduction construction, in which a piece, square in cross-section, is 15 as reduction proceeds changed in cross-section to a diamond and square alternately, the final reduction pass being square. An arrangement of passes in the respective pairs of rolls, suitable for such method of rolling 20 is diagrammatically shown in Fig. 5 and Fig. 6. Passes *a* and *b* are diamond shaped while passes *c*, *d*, *e*, *f*, and *g* are alternately square and diamond. As the rolls 1 feeds onto the delivery table B and as the finished articles 25 should be square in cross-section, the last pass *g* in the rolls 1 should be square as shown in Fig. 5 and as there must be an uneven number of passes to ensure the feeding for the last pass onto the delivery table, 30 and this pass is square, it follows that two succeeding passes, as for example *a* and *b* will be the same shape, i. e., diamond.

In the operation of the mill, the pieces are placed in succession on the receiving table 35 A, and a piece fed to pass *a*, the piece moves over the rolls 2 onto the rollers of table B. The piece is now turned on its axis but not moved laterally and the mill shifted to bring rolls 2 to operative position, said operations being preferably simultaneous, as 40 will be hereinafter described.

The feed rollers of both tables being reversed, the piece is fed to pass *b* in rolls 2, which as before stated, is diamond shape 45 and moves over rolls 1 into the first groove in the rollers of table A. This piece is now turned axially and shifted laterally into alignment with the pass *c*, which is a square, and the mill shifted to bring rolls 1 into 50 operative position. A second piece being placed in the first groove in the rollers of table A, the rollers of both tables are rotated to feed the pieces to rolls 1 from which they pass onto table B. Both pieces are now 55 turned on their axes but not moved laterally, the mill shifted and the articles fed through the diamond passes *b* and *d* in rolls 2. These operations are repeated, a new piece being placed in position on table A, as previous 60 pieces are shifted laterally. As the last shaping pass is in rolls 1 as hereinbefore described, a finished piece will be delivered, if the mill is full, on each operation of the rolls 1.

65 While the invention in its broadest aspect

is not limited to specific constructions of mechanisms, for turning and shifting the pieces being rolled, the mechanisms shown herein have been found to be particularly well adapted to those ends. The mechanism 70 for shifting the pieces from one groove to an adjacent groove of the feed rollers 26 of table A, is clearly illustrated in Figs. 7 to 10 inclusive and consist of fingers 27 which are so moved as to push the pieces laterally 75 up the side of the groove and the lateral movement is continued causing the piece to move across the ridges intermediate adjacent grooves. As the pieces move across the ridges, the preponderating weight of the portions which have passed beyond the ridges combined with the upward pressure of the fingers against the opposite edges of the pieces will cause an axial turning of the pieces and their dropping into the adjacent 80 grooves. The grooves are so shaped that the pieces will be held in proper position to enter the square passes in rolls 1. The desired upward and lateral movements of the portions of the fingers in contact with the 85 pieces being shifted can be effected preferably by making the fingers portions of levers 28, pivotally mounted in frames 29, secured to the sides of the frames of the feed tables. These levers have their lower ends connected 90 by pitmen 30 to arms 31 on a shaft 32, which is rotated by shaft 8 through intermeshing bevel pinions 33 as shown in Figs. 1 and 7, so that the shifting and turning of the pieces 95 on table A is effected simultaneously with the movement of the mill whereby the rolls 1 are brought to operative positions.

In Figs. 11 to 14 inclusive, is shown mechanism adapted to turn the pieces around their axes, but without changing their positions horizontally. A slotted frame 34 is arranged transverse of the feed table B, being supported by the sides of said table. The side bars of the frames 34 are slotted as 100 at 35 for the reception of the ends of pins 36, on which are pivotally mounted slotted arms 37. These pins are connected together and to a pin 38, passing through a slotted hanger 39 by a bar 40, the pin 38 projecting into the slots 35 in the side bars of the frame 110 34. The hanger is pivotally suspended from a pin 41, the ends of which project into vertical slots 42 in the standard or post 43 on the frame 34. A bar 44 is connected by a pin 45 to the hanger at a point intermediate its ends and to the arms 37 at points suitable distances above their pivotal pins 36, by pins 46. The upper ends of the arms 37 are provided with plates or seats 47 for supporting the pieces to be turned during 115 such turning movement. The hanger is connected by a pitman 48 to an arm 49 on the shaft 50, which is rotated by the shaft 7 through the medium of bevel pinions 51 so that the turning devices are operated while 120 125 130 135

the mill is being shifted to bring the rolls 2 into operative position.

Normally, the arms 37 are in such an angular position that the faces of the plates 5 or seats will be nearly parallel with sides of the pieces to be turned, as shown in Fig. 12. As the shaft 50 is rotated, the arms are moved laterally, the lower ends of the arms moving more rapidly than the seats. 10 As the pins 36 project into the slots 35, the arms will move vertically as well as laterally, thus bringing the plates or seats 47 into contact with the sides of the pieces. As the arms continue their movement to the 15 right and also their vertical movement the pieces are raised high enough in the grooves in the feed rollers to permit of their rotation. When the arms are in mid position or vertical position, the vertical movement ceases. 20 As the movement of the arms to the right continues, there will be a further turning on a gradual lowering of the pieces into the same grooves of the rollers. It will be observed that in the above described operation, the seats 47 are shifted from one side of the respective grooves in the rollers and in such shifting are turned through an 25 arc of ninety degrees. After the pieces on table B have been turned, the feed rollers 30 are operated to feed the pieces to reducing rolls, so that the movement of the turning devices to normal position will not be interfered with. This restoration of the manipulating devices of one table to normal 35 position is effected while those of the other table are being operated to effect the desired change of position of the pieces on the other table.

I claim herein as my invention:

40 1. A rolling mill having in combination two pairs of reducing rolls, means for bringing such pairs alternately into operative position, feed tables having reversible rollers arranged on opposite sides of the reducing rolls, means for laterally shifting and axially turning articles being rolled on one table and means for axially turning the articles on the other table while in substantial alinement with the pass by which it was 45 delivered onto said table.

50 2. A rolling mill having in combination two pairs of reducing rolls, means for moving said pairs alternately into operative position, feed tables having reversible rollers arranged on opposite sides of the reducing rolls, means for shifting and axially turning the piece being rolled on one of the tables and means for operating such turning and shifting means simultaneously with 55 the movement of the rolls fed by said tables into operative position.

60 3. A rolling mill having in combination two pairs of reducing rolls, means for moving said pairs alternately into operative position, feed tables having reversible rollers

arranged on opposite sides of the reducing rolls, means for turning the pieces being rolled on one table while maintained in substantial alinement with the pass by which it was delivered onto said table and means 70 operating such turning means simultaneously with the movement of the rolls fed by said table into operative position.

4. A rolling mill having in combination reducing rolls, a feed table having reversible grooved rollers, and means for laterally moving the piece being rolled up the side walls of the grooves in the rollers and so moving the piece across the ridge intermediate adjacent grooves that it will automatically tip and drop with a turning movement, into the adjacent groove. 75

5. A rolling mill having in combination reducing rolls, a feed table having reversible grooved rollers, a plurality of plates 80 normally supported on one side of a vertical plane coincident with the lowest portions of the grooves in the rollers and at an angle to such plane, and means for simultaneously shifting said plates to the opposite side of said plane and turning them through an arc of ninety degrees or approximately ninety degrees. 90

6. A rolling mill having in combination grooved reducing rolls, a feed table having reversible rollers, a frame arranged intermediate adjacent rollers, movable arms carried by said frame and normally supported at an angle to the axes of the rollers and on one side of vertical planes passing through grooves in the rolls and means for moving said arms to the opposite side of said plane and reversing their angular relation to the axes of the rollers. 95

7. A feed table for rolling mills having in combination reversible driven rollers, frames arranged intermediate adjacent rollers, arms movably mounted in said frames and normally at an angle to and on one side of vertical planes at right angles to the axes of the rollers, means for moving said arms to the opposite side of said planes, the lower ends of the arms being moved at a higher rate than the upper ends and maintained in the same horizontal plane 110 during such movement. 115

8. A feed table for rolling mills having in combination grooved reversible driven rollers, a frame arranged intermediate adjacent rollers, fingers pivotally mounted in said frame the pivotal points of said fingers being in vertical planes intersecting the rollers intermediate adjacent grooves and in normal position extending across and below the paths of movement of pieces lying 120 in said grooves and means for shifting said fingers. 125

9. A feed table for rolling mills having in combination grooved reversible driven rollers, a frame arranged intermediate ad- 130

jacent rollers, levers pivoted in said frame, said levers having their pivotal points in vertical planes intersecting the rollers intermediate adjacent grooves and having the portions above the pivotal points normally extending across but below the path of movement of pieces in the grooves in the

rollers and means connected to the lower ends of the levers for shifting pieces from one line of grooves to adjacent grooves. 10

In testimony whereof, I have hereunto set my hand.

JOSEPH E. FAWELL.
